UNITED STATES PATENT OFFICE.

THOMAS A. SOULTS, OF ROCHESTER, NEW YORK, ASSIGNOR TO SILL STOVE WORKS, OF ROCHESTER, NEW YORK, A CORPORATION OF NEW YORK.

DAMPER MECHANISM FOR GAS-STOVES.

1,330,989.

Specification of Letters Patent.

Patented Feb. 17, 1920.

Application filed December 14, 1916. Serial No. 136,905.

To all whom it may concern:

Be it known that I, THOMAS A. SOULTS, of Rochester, in the county of Monroe and State of New York, have invented certain new and useful Improvements in Damper Mechanism for Gas-Stoves; and I do hereby declare the following to be a full, clear, and exact description of the same, reference being had to the accompanying drawings, forming a part of this specification, and to the reference-numerals marked thereon.

My invention has for its purpose to provide a damper mechanism for gas stoves and gas ranges of the type which are connected with an outlet flue or chimney for carrying off smoke and products of combustion, the parts being related in such a manner as to effectively prevent accidental extinguishing of the gas flame from a sudden back draft or accumulation of back pressure from the flue. A further purpose of my improvement is to carry off the products of combustion, smoke and unburned gases into the flue under ordinary operating conditions when a draft is acting properly, and also to permit a ready outlet from the flue of any gases or air currents that may be driven down the flue by a reversed draft, thus preventing their having access to the flame or fire. To these and other ends the invention consists in certain improvements and combinations of parts, all as will be hereinafter more fully described, the novel features being pointed out in the claims at the ends of the specification.

In the drawings:

Figure 1 is a plan view, with parts broken away, of a combination coal and gas stove embodying a preferred arrangement of my invention;

Fig. 2 is a sectional view on line 2^a—2^a of Fig. 1;

Fig. 3 is a sectional view on line 3^a—3^a of Fig. 1; and

Fig. 4 is a sectional view on line 4^a—4^a of Fig. 1.

Similar reference numerals in the several figures indicate the same parts.

The structure which I am about to describe is intended merely as illustrative of one manner of carrying out the invention, which is applicable in different relations, whether it be to a gas stove or gas range simply, or to a combination structure involving both a coal burning section and gas burning section, and

in its broad conception may be said to include a secondary outlet or flue which is associated with the gas stove or gas burning section and also with the main outlet or flue for carrying off unburned gases and products, while at the same time having a permanent opening or outlet to the atmosphere immediately surrounding the stove. The opening or outlet last mentioned is under normal conditions without function, and serves its purpose only when a back draft or reverse current is present in the flue and is diverted from its otherwise natural course to the fire, and exhausted outwardly through said opening into the room or chamber containing the stove. In the majority of instances, strong back drafts occur only for a moment or so, but continue for a sufficient length of time, not infrequently, and with enough pressure to extinguish a gas flame, and as this usually occurs without warning or notice of any sort, disastrous results usually follow from the accumulation of escaping gas in the stove or room.

In the present structure, 1 designates the main body or structure of the stove while 2 is an oven which may be heated from the gas burner 3 or from the heat of coal in the fire box 4 when coal is burned on the grate 5. 6 designates the main flue or outlet which may be connected in the usual manner with the coal burning section of the stove for carrying off smoke and products of combustion, while 7 designates a secondary flue that is in communication with the main flue 6 through an opening 8. The secondary flue 7 communicates with the oven 2 through the flue 9 and openings 10 and 11, as indicated in Fig. 3. The opening 11 is preferably controlled by a damper 12, which is also operatively connected to a damper 13 governing the burner chamber 14 and preferably connected with the gas cock so that when the latter is opened to furnish a supply of fuel, the dampers or valves 12 and 13 are simultaneously opened to establish communication between the gas burner 3 and the secondary flue 7. Burners 15 are also arranged at the upper part of the stove in a chamber 16 which is in direct communication with the secondary flue 7, as shown in Fig. 3. The secondary flue 7 is open at one end, as indicated by 17, affording an outlet to the atmosphere surrounding the stove, and it will be observed that the outlet 17 is dis-

posed oppositely to the opening 8 communicating with the main flue 6, and is thus in the direct path of any back draft or reverse current that may be induced in the secondary flue 7. 18 designates a damper controlled by the handle 19 and operating to close the opening 8 if desirable for any reason, as for instance when starting a coal fire when the chimney is cold or other conditions make it expedient by reason of imperfect draft. As soon as the proper combustion and draft is obtained in the coal section of the stove, there is no further need for maintaining the damper 18 closed, and when it is desirable to use the gas burning section of the stove, the damper 18 is opened in order to afford access into the main flue for the products of combustion from the gas burners. In the event of any back draft occurring and reaching the secondary flue 7, it naturally follows the most direct course and is exhausted through the opening 17 into the atmosphere, and thus prevented from reaching the burners of the stove and affecting the gas flame. In the event that the damper 18 is left closed while the gas burners are in operation, no serious harm can result, as the products of combustion merely pass out through the opening 17 into the surrounding atmosphere, and under any condition, whether the gas secondary flue is in communication with the main flue or not, it is impossible for any air currents or draft to find their way back to the burners, which therefore cannot be accidentally extinguished.

While I have referred particularly to gas stoves and gas burners, I intend to cover by this application, all uses of my invention as applied to any gaseous or liquid fuel burners, and it will be understood that the claims are to be construed as covering any such gaseous or liquid fuel stove.

I claim as my invention:

1. In a gas stove, the combination of a burner chamber, a main flue, a secondary flue communicating with said main flue and with said burner chamber and having an opening communicating with the atmosphere surrounding the flue, and a damper for closing the opening communicating with the main flue without obstructing the opening communicating with the atmosphere.

2. In a gas stove, the combination of a burner chamber, a main flue, a secondary flue communicating with said main flue and with said burner chamber and having an opening communicating with the atmosphere surrounding the flue, and a damper opening into the main flue and movable to close the opening from the secondary flue to the main flue without obstructing the opening in the secondary flue communicating with the atmosphere.

3. In a stove, the combination of upper and lower burner chambers, a main flue, a secondary flue having openings communicating with said main flue, said upper and lower burner chambers and open to the atmosphere surrounding the flue, a damper for closing the opening communicating with the lower burner chamber and a second damper movable to open and close the opening between the main and secondary flues.

4. In a stove, the combination of upper and lower burner chambers, a main flue, a secondary flue having openings communicating with said main flue, said upper and lower burner chambers and open to the atmosphere surrounding the flue, dampers controlling the admission of air to and escape of the products of combustion from said lower chamber, and means controlling the opening between the main and secondary flues.

THOMAS A. SOULTS.
